DESIGN FOR A PICTURE MOUNT OR SIMILAR ARTICLE

Rex Hendrix, Brooklyn, N. Y.

Application September 9, 1944, Serial No. 115,250

Term of patent 7 years

(Cl. D61—1)

To all whom it may concern:

Be it known that I, Rex Hendrix, a citizen of the United States, residing at Brooklyn, in the county of Kings and State of New York, have invented a new, original, and ornamental Design for a Picture Mount or Similar Article, of which the following is a specification, reference being had to the accompanying drawing, forming part thereof.

I claim:

The ornamental design for a picture mount or similar article, substantially as shown.

REX HENDRIX.
